UNITED STATES PATENT OFFICE.

ADAM HOFFMANN, OF ALLEGHENY, PENNSYLVANIA.

RAILROAD-SIGNAL.

SPECIFICATION forming part of Letters Patent No. 313,936, dated March 17, 1885.

Application filed March 3, 1884. (No model.)

To all whom it may concern:

Be it known that I, ADAM HOFFMANN, a citizen of the United States, residing at Allegheny, in the county of Allegheny and State of Pennsylvania, have invented certain new and useful Improvements in Railroad-Signals, of which the following is a specification, reference being had therein to the accompanying drawings.

10 My invention relates to an improvement in devices for giving trains running on a single-track railroad notice of an approaching train from an opposite direction by sounding an alarm-bell in the engineer's cabin; and it consists in the combination of cranked shafts which operate under the rails, operating-levers connected to the cranks, rods which extend along the track, and signal-levers which are operated by the rods, as will be more 20 fully described hereinafter.

The accompanying drawings represent my invention. Figure 1 is a plan showing sections of a railroad to which the device is applied; Fig. 2, a side view of the same. Fig. 25 3 is a diagram illustrating the manner of placing the rods. Fig. 4 represents a car-wheel on a treadle; Fig. 5, the hanger, a signal-rod, and the connection with the bell.

In describing my invention it is to be understood that at both sides of the railroad the device for sending ahead an alarm is alike, and what is stated about the appliance hereinafter is applicable to both sides of the road.

30 A represents detached sections of a single-track railroad, of which B are the ties and C the rails. Parallel with and near to the latter are two interrupted lines of iron rods, D, guided in staples on top of the ties to hold them in place, but allowing them to be moved horizontally back and forward. The rods D are of a length to enable the engineer of a train in motion, when an alarm is received, to arrest its progress before or at the time when it arrives at the end of the rod which 40 gives the signal. On either side of the track is placed a rod, D, which should preferably be about three thousand feet long. A second similar rod is placed parallel to the rod D, overlapping it about one thousand feet, or 45 one-third of its length. This arrangement is proceeded with to the end of the line, a space of about one thousand feet, or one-third the

length of the rods, being left between the rods where they are separated, as shown at Fig. 3.

55 The mechanism by which the signaling is accomplished is hereinafter set forth; but the operation of the overlapping rods may be fully described here. Train A', traveling in the direction indicated by the arrow, arriving at a', 60 sends the alarm ahead three thousand feet to b'. The train B', running in the opposite direction, having arrived at or near b', receives the alarm one thousand feet, or more, in advance of A', and has time to stop or reverse 65 its engine, and the reverse takes place if B' sends the alarm ahead. By this means two trains running in opposite directions can communicate with one another, which they cannot do by one or two continuous lines. There 70 will be always at least one-third of the length of the rods between two trains when they are notified of each other's approach, or as great a distance as is left open between the rods.

75 At the sides of the ties B, under the rods D, at suitable distances from one another, are hinged short signal-rods a with slots x, through which the rods D pass, and on the rods D are collars or pins y, that prevent their sliding through the slots when drawn to either side, 80 that by moving the rods D the signal-rods a are made to stand erect or to incline toward the ground.

Near the ends of the rods D are crank-shafts 85 b, passing under the rails from one side of the track to the other, secured in place in any suitable manner to revolve, and to one end of each is rigidly attached a lever, d, to the end of which the rod D is pivoted. The throw of the crank on the shaft b is up and down entirely beneath the rail, and over it a treadle, 90 g, close to the rail, with its rear end hinged to the nearest tie, and its forward end raised higher than the adjoining rail, so as to become depressed by the wheels of a train arriving at the hinged end of the treadle. The side toward the rail of the raised end of the treadle g is cut slanting to form an opening for the wheels of a train coming from that side to enter and push away the treadle from the 95 rail without depressing it, to be immediately returned to its former position, after the passage of the train, by the spring S on the crank.

100 Under the treadle is a loop, through which

- the crank passes, causing the crank to turn down at each depression of the treadle. The lever *d*, affixed to the crank-shaft, being moved when the crank is pressed down by the treadle, 5 draws the rod *D* with it, causing the treadle on the other end of the same rod and the signal-rods *a* along the whole length of it to rise. If, then, the rod *D* were three thousand feet long, the signal-rods would be raised three 10 thousand feet ahead of the train, which signals, when the train passes over the second treadle at the end of the same rod, are again bent low, and the first treadle raised up by the contrary motion of the rod. Before arriving, however, 15 at the end of this same rod the wheels meet the treadle on the end of the next rod, and send the signal ahead before the former rods are bent down again, and this is repeated until the train stops.
- 20 The end of the crank-shaft *b* opposite the treadle is bent at a right angle, *h*, and to this end is pivoted a rod extending back a short distance to a single signal-rod, *i*, which, when the treadle opposite to it is depressed, is raised 25 to give notice to a following train of the nearness of a train ahead. This signal is again bent down when the treadle is raised at the passage of the wheels over the second treadle on the same rod *D*.
- 30 Under one side of the engine is a hanger, *E*, in the lower end of which is pivoted a lever, *Z*, which is connected at one end by a chain with a bell in the engineer's cabin, which lever comes in contact with the signal-rods 35 raised ahead by a train approaching from an opposite direction. If the hangers are placed on the left side under the engine, they strike the signals on that side, but those on the right hand are not struck by said engine, and as 40 each engine raises the signals on the side opposite to its hangers no false alarm can be given.

In case two engines running in the same direction should arrive at about the same time at the two ends of one of the rods *D*, and the 45 one at the right of Fig. 1 should be upon lever *g* when the engine at the other end should be running upon its lever *g*, a break would unavoidably occur. This is prevented by placing a spring, *f*, at one end of each rod *D*, a

spring strong enough to resist the ordinary 50 action of a single train passing over the treadle, but yielding when two of them are brought to bear against it at the same time.

The treadles *g* are so adjusted at the ends of the rods *D* that the first one arrived at is depressed to the level of the rails, and the one 55 at the other end thereby raised up to come successively in contact with the wheels and be depressed, whereby the former is raised up ready for a following train to give the signal 60 to any approaching train from the opposite direction. The rods *D* are thus at every passage of a train drawn back and forth, and the signal-rods raised to give a warning in advance, to again be lowered when the wheels have 65 passed over the second treadle on the same rod.

Instead of only using one hanger, two may be hinged to an engine, one at each side, so that either one can be raised up to avoid a 70 contact with the signals when running backward.

Having thus described my invention, I claim—

1. In a railroad-signal, the combination of 75 the track, the rods *D*, placed alongside thereof and made to overlap each other, cranks, levers for moving the rods, and signal-rods which are operated by the endwise movement of the rods, substantially as shown.

2. In a railroad-signal, the combination of 80 the track, the rods *D*, placed alongside thereof and made to overlap at their ends, cranks, operating-levers connected to the cranks, signal-rods, and a mechanism on the locomotive 85 which is for sounding an alarm and which is operated by the signal-rods, substantially as described.

3. The combination of the rods *D*, crank-shafts *b*, treadles *g*, levers *d*, and springs *S*, arranged substantially as set forth.

In testimony whereof I affix my signature in presence of two witnesses.

ADAM HOFFMANN.
